DESIGN FOR A FLYING BOAT

Robert J. Minshall and Wellwood E. Beall, Seattle, Wash., assignors to Boeing Aircraft Company, Seattle, Wash., a corporation of Washington

Application June 1, 1936, Serial No. 62,948

Term of patent 7 years

To all whom it may concern:

Be it known that we, Robert J. Minshall and Wellwood E. Beall, both citizens of the United States and both residing at Seattle, in the county of King and State of Washington, have invented a new, original, and ornamental Design for a Flying Boat, of which the following is a specification, reference being had to the accompanying drawing, forming part thereof.

Figure 1 is a plan view of the flying boat, illustrating our new design.

Figure 2 is a side elevation of the flying boat.
Figure 3 is a front elevation of the flying boat.
Figure 4 is a perspective view of the flying boat, in flight.

We claim:

The ornamental design for a flying boat, as shown.

ROBERT J. MINSHALL.
WELLWOOD E. BEALL.
